Primary Examiner—Ian Simmons*Assistant Examiner*—Mark A Goodwin(74) *Attorney, Agent, or Firm*—Warner Norcross & Judd LLP(57) **CLAIM**

The ornamental design for a tong, as shown and described.

DESCRIPTION

FIG. 1 is a perspective view of the tong embodying my new design;

FIG. 2 is a front elevational view thereof;

FIG. 3 is a rear elevational view thereof; and

FIG. 4 is a right side elevational view thereof;

FIG. 5 is a left side elevational view thereof;

FIG. 6 is a top plan view thereof; and,

FIG. 7 is a bottom plan view thereof.

FIGS. 1–7 show portions of the tong in broken lines. These features are shown for environmental purposes and do not form any part of the claimed design.
